(Cl. D36—8)

To all whom it may concern:

Be it known that I, Raymond W. Kell, a citizen of the United States of America and a resident of Columbus, in the county of Franklin and State of Ohio, have invented a new, original, and ornamental Design for a Glass Tumbler or Article of Similar Nature, of which the following is the specification, reference being had to the accompanying drawing, forming a part hereof.

Figure 1 is a perspective view of a glass tumbler or article of similar nature, showing my new design.

Figure 2 is a vertical sectional view thereof; and

Figure 3 is a top plan view.

I claim:

The ornamental design for a glass tumbler or article of similar nature, substantially as shown.
RAYMOND W. KELL.
